Maier & Neustadt, L.L.P.(57) **CLAIM**

The ornamental design for a cap removal device, as shown and described.

DESCRIPTION

FIG. 1 is a front and bottom perspective view of a cap removal device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

The broken lines depict portions of the cap removal device that form no part of the claimed design.
